UNITED STATES PATENT OFFICE.

ARTHUR M. EICHORN, OF NEW YORK, N. Y.

CLEANING ATTACHMENT FOR AUTOMATIC TELEPHONE DIALS.

Application filed November 13, 1925. Serial No. 68,772.

This invention relates to automatic dial operated telephone apparatus and has particular reference to means for insuring that the dial thereof shall be kept clean of dust, 5 dirt, or the like coincident with the normal manipulation of the mechanism.

From the nature of the construction and its operation the dial, the portion that bears on its surface the numerical or literal indicia, is always exposed to the atmosphere and hence is subjected to the accumulation thereon of dust or dirt which is an occasion for several disagreeable conditions and which can not under ordinary circumstances 10 be remedied with convenience by the means of cleaning devices: First, the accumulation of the dust obscures or tends to obscure the indicia on the dial rendering the same more difficult of observation, and, secondly, while 15 using the device in the usual manner the operator's finger sweeps or wipes over the face of the dial and consequently the finger so used is continuously being soiled from the accumulation of dust or dirt.

20 Among the objects of this invention therefore is to apply to the automatic mechanism above referred to a simple wiping or cleaning member that serves automatically, and hence without thought or care on the part 25 of the user, to keep the dial swept clean, thereby obviating the objections above enumerated, and without interfering with or disturbing the normal operation of the instrument or presenting a conspicuous appearance.

With the foregoing and other objects in view the invention consists in the arrangement and combination of parts hereinafter described and claimed, and while the invention 30 is not restricted to the exact details of construction disclosed or suggested herein, still for the purpose of illustrating a practical embodiment thereof, reference is had to the accompanying drawings in which like reference characters designate the same parts in the several views, and in which—

Figure 1 is a plan view of the actuating disk and parts associated directly therewith.

Fig. 2 is a side elevation of the parts just described, partly in section, on the line 2—2 of Fig. 1, and with the telephone base tilted upward into perspective.

Fig. 3 is a sectional perspective view of 55 one of my improved cleaners.

Fig. 4 is an enlarged perspective view of

the cleaner complete but detached from the mechanism.

Fig. 5 is a detail view of a modification.

Referring now more specifically to the drawings, B indicates the base of a standard telephone instrument, and S is the standard or stem thereof. Fixed to the base and in slightly inclined position in relation thereto is the switch casing 10 having formed upon the upper surface thereof a series of circular indicia constituting what is described herein as the dial 11. A finger stop member 12 is secured in fixed position upon the periphery of the casing 10 and extends at its outer and inner end inward over the dial and spaced therefrom.

Between the stop 12 and the dial and journaled for rotation around the axis of the dial is the actuator 13 in the nature of an annulus or disk provided with a series of ten holes 14 registering respectively with the indicia units on the dial 11. In the normal operation of this automatic mechanism, the user in calling a station applies his finger in succession in or through certain of the holes 14 according to the exchange and number sought, and when the finger is so applied in each hole, the finger actuates the actuator ring in a clockwise direction until stopped by the member 12, this operation being continued until the call is completed. It follows therefore that such use or movement of the finger is almost certain to result in the tip of the finger becoming soiled from the dirt or dust usually accumulating on the face of the dial.

In order to obviate the objections above stated I provide a cleaning member comprising a ring or short thimble 15 having on its outer surface a groove 16, and shown as split at 17 along one side. This thimble is so designed that when contracted as a result of pressure applied to the sides as per arrows a, it may be introduced into any one of the holes 14, preferably the one close beneath the stop 12, and because of the inherent resiliency of the thimble, it will then spring open so as to receive the rim of such hole into the groove 16 and so be self-retained in place. While the device may be inserted into any of the holes it is found preferable to insert it into the one specified and shown in Fig. 1 for several reasons: First, when placed in the hole indicated and the actuator is manipulated from such hole, a complete sweep of the dial is assured, and, sec-

ondly, the hole just specified is one that registers with the "0" of the dial, a character that is used more frequently than any other character in this system, and consequently the sweeping system is practised for this reason much more frequently than if it be applied in any other hole.

Secured in any suitable manner in or to the under side or edge of the thimble 15 is a wiping member or squeegee 18, which may be of any suitable material such as felt, leather, soft rubber, hair, or the like. This member too is shown as of an annular form with one side split at 19 in line with the split 17 of the thimble, and without limiting myself unnecessarily to any specific material construction I indicate that the upper edge of the squeegee may be fitted into and secured in a groove 20 formed in the lower or inner edge of the thimble. The cleaning device constructed and applied as shown does not obstruct in any way the clear reading or observation of the indicia upon the dial, and, moreover, the thimble receives the user's finger in precisely the same manner as it is received in any other hole of the actuator. It follows therefore that the presence of the device is in no manner objectionable either to the use and manipulation of the instrument or to the technical operation of the system. The immediate result, however, is that whenever the actuator is rotated the squeegee wipes easily but effectively over the face of the dial, and keeps the dial swept or brushed clean of dust or dirt throughout the sweep of the cleaner in any instance. When, however, the actuator is manipulated from the hole bearing the cleaner, the sweep is complete throughout the extent of the series of indicia. It is practically assured, therefore, that every use of the instrument for the making of a call will thoroughly cleanse the dial, and when the instrument is used frequently during the day no accumulations of dust or dirt can result with the accompanying soiling of the user's finger during the initial manipulation in the making of the next call.

Obviously the material of the thimble may be according to the demand and may be of hard rubber, metal, or any other material which is of sufficient body for the purpose and which has a certain inherent flexibility so as to snap readily into place. As shown in Fig. 5 the thimble 15^a is made of sheet metal so rolled or formed as to provide a rim overlapping the rim of the hole 14 into which it is fitted and having the squeegee gripped between the edge portions of the metal or other material as at 20^a.

I claim:

1. The combination with a member having a series of selective indicia on its face and a manually operated actuator movable to variable extents thereover, said actuator having selective finger holes therethrough registering with the indicia aforesaid, of a cleaning member fitted in the region of one of said holes and movable as a result of the movement of the actuator over the surface of said indicia.
2. Mechanism as set forth in claim 1 in which the cleaning member comprises a thimble having an open center to afford an unobstructed vision through the hole in which it is fitted.

In testimony whereof I affix my signature.
ARTHUR M. EICHORN.
